US00D785893S

(12) **United States Design Patent** (10) Patent No.: **US D785,893 S**
(45) Date of Patent: ** May 2, 2017

(54) **GIMBAL**

- (71) Applicant: **SZ DJI Technology Co., Ltd.**, Shenzhen, Guangdong (CN)
- (72) Inventors: **Min Kim**, Shenzhen (CN); **Paul Pan**, Shenzhen (CN); **Yan-Chong Zhao**, Shenzhen (CN); **Hao Liu**, Shenzhen (CN)
- (73) Assignee: **SZ DJI Technology Co., Ltd.**, Shenzhen (CN)
- (**) Term: **15 Years**
- (21) Appl. No.: **29/567,823**
- (22) Filed: **Jun. 13, 2016**

Related U.S. Application Data

- (63) Continuation of application No. 29/513,070, filed on Dec. 25, 2014, now Pat. No. Des. 759,335.

(30) **Foreign Application Priority Data**

- Jun. 27, 2014 (CN) 2014 3 0207007

- (51) LOC (10) Cl. **12-05**

- (52) U.S. Cl.

- USPC **D34/28**

(58) **Field of Classification Search**

- USPC ..... D34/28, 32, 33; 254/89 H, 89 R, 134, 254/98 H

- CPC B66F 9/08; B25F 1/0007; G11B 5/4826

See application file for complete search history.

(57) **CLAIM**

The ornamental design for a gimbal, as shown and described.

DESCRIPTION

FIG. 1 is a top front perspective view of a gimbal showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof showing the gimbal in an environment in which it may be used.

The broken lines in the figures show portions of the gimbal and environment that form no part of the claimed design.

1 Claim, 8 Drawing Sheets

FIG. 1

FIG. 2

FIG. 3

FIG. 4

FIG. 5

FIG. 6

FIG. 7

FIG. 8
